The ornamental design for a barrel tie-down bracket, as shown and described.

DESCRIPTION

FIG. 1 is a top, front, left side perspective view of a barrel tie-down bracket according to a first embodiment of the invention.

FIG. 2 is a bottom, back, right side perspective view thereof. FIG. 3 is a top plan view thereof.

FIG. 4 is a bottom plan view thereof.

FIG. 5 is a right side plan view thereof, the left side plan view being a mirror image thereof; and, FIG. 6 is a front plan view thereof, the back plan view being a mirror image thereof.

Shading lines are used to show solid structures and are not intended to indicate surface decoration.
